UNITED STATES PATENT OFFICE.

WALTER O. BORCHERDT, OF AUSTINVILLE, VIRGINIA, ASSIGNEE TO THE NEW JERSEY ZINC COMPANY, OF NEW YORK, N. Y., A CORPORATION OF NEW JERSEY.

APPARATUS FOR TREATING PULPS.

Original application filed June 4, 1919, Serial No. 301,833. Divided and this application filed January 27, 1923. Serial No. 615,245.

To all whom it may concern:

Be it known that I, WALTER O. BORCHERDT, a citizen of the United States, residing at Austinville, in the county of Wythe, State 5 of Virginia, have invented certain new and useful Improvements in Apparatus for Treating Pulps; and I do hereby declare the following to be a full, clear, and exact description of the invention, such as will enable others skilled in the art to which it 10 pertains to make and use the same.

This invention relates to apparatus for treating pulps and has for its object the provision of an improved apparatus of this 15 character, and more particularly the provision of an improved apparatus for carrying out the differential sedimentation of the solid particles of a pulp, such, for example, as an ore or mineral pulp.

20 In my application for Letters Patent of the United States, Serial No. 301,833, filed June 4, 1919, for improvements in the treatment of concentrates, there is disclosed a method of treating mineral concentrates, and 25 more particularly flotation concentrates, containing colloidal matter, which comprises subjecting the concentrate in the form of a pulp to appropriate treatment for dispersing or deflocculating the colloidal constituents therein and subsequently separating the valuable mineral particles of the pulp 30 from the dispersed colloids and the gangue particles by sedimentation of the former and decantation of the latter, and preferably by 35 "hindered" settling so as to effect differential sedimentation of the solid particles of the pulp. The present invention is particularly directed to the provision of an improved apparatus for carrying out "hindered" settling of a pulp under appropriate 40 conditions for securing differential sedimentation of the solid particles of the pulp.

The apparatus of the invention comprises 45 a tank relatively deep as compared with its other dimensions and provided with appropriate means for permitting the separate removal or withdrawal therefrom of settled solid particles of the principal mineral, the final top layer of lighter secondary mineral 50 and of supernatant liquor. Within the tank appropriate instrumentalities are provided, preferably one or more resilient members, such as chains secured at their lower ends near the bottom of the tank and arranged to

be reciprocated to a desired extent at their 55 upper ends, for effecting a gentle disturbance of the upper portion of the settled but unconsolidated sediment in the tank so as to permit differential sedimentation and separation of solid particles. Intermediate its 60 top and bottom the tank is preferably provided with an outlet for the withdrawal of material therefrom. Appropriate means are also provided for conducting or feeding pulp into the tank preferably with the least 65 possible disturbance of the contents thereof. In practice, the tanks are preferably arranged in pairs so that the filling of one tank with pulp may be effected while the 70 contents of the other tank is undergoing removal.

In the accompanying drawings I have 75 illustrated what I now believe to be the best modes of carrying out the invention. In these drawings,

Figure 1 is a sectional elevation of an apparatus embodying the principles of the invention;

Figure 2 is an elevation of a pair of cooperating tanks of the construction illustrated 80 in Figure 1;

Figure 3 is a detail view illustrating a modified arrangement for reciprocating the upper ends of the resilient members suspended within the tank; and

Figure 4 is a sectional elevation of an apparatus provided with a modified instrumentality for effecting a gentle disturbance of the upper portion of the settled but unconsolidated sediment in the tank.

Referring now to Figures 1 and 2 of the accompanying drawings there is represented an apparatus comprising a platform 5 upon which is mounted a pair of tall settling tanks 6. These tanks have a considerable 95 depth as compared with their other dimensions, and the interior vertical section of each tank has the configuration of a frustum of a cone or pyramid with the larger end resting on the platform 5. The platform 5 and tanks 6 may be built of any appropriate material. I have found steel, wood or concrete well adapted for this purpose.

Each tank 6 is provided at its bottom with 105 a clean-out opening or door-way 7, through which the settled solid particles may be removed or withdrawn from the tank. During

sedimentation or settling, the door-ways 7 are closed by door plates 8, which are preferably secured to the tanks, as for example, by bolts 9, so as to form a water-tight joint 5 with their respective tanks. During the cleaning out operation, the door plate 8 may be swung out of the way by means of a cable and cooperating pulleys 10 suspended from a support 11 secured to the upper end of 10 the tank 6. The position of the door plate 8 when thus swung out of the way is indicated by dotted lines in Fig. 1.

A trough 12 is positioned in front of the openings or doors 7 for receiving the settled 15 solid particles withdrawn from the tanks. A car-loading elevator 13 carried by an appropriate truck mounted on tracks 14 is operatively arranged to dig the solid particles out of the troughs 12 and to discharge the 20 same into a car 15 standing on tracks 16. The tracks 14 and 15 may be arranged in front of a series of tanks 6 so as to permit the convenient loading, by movement of the elevator 13, of the solid particles withdrawn 25 from any tank in the series.

The pulp to be treated is delivered to each tank 6 through a perforated pipe 17, which communicates at its top with a main pulp supply pipe 18 and is provided with a valve 30 19 for controlling the pulp supply. The pipe 17 extends throughout the entire length of the tank 6 and is provided with discharge outlets at frequent intervals throughout its whole length within the tank, whereby the 35 pulp can be fed into the tank with the least possible disturbance of the contents thereof. An outlet or overflow pipe 20 communicates with the interior of the tank near the top thereof and serves to conduct supernatant 40 liquor to a settling tank (not shown) or other appropriate place of disposal. A second outlet or overflow pipe 21 communicates with the interior of the tank at an appropriate distance below the pipe 20. The pipe 45 21 is provided with a valve 22 and is arranged to discharge into a ditch or trough 23 which may conveniently be formed in the platform 5.

Brackets 24, mounted on top of the tanks 50 6, support bearings 25 in which is mounted a shaft 26 carrying arms 27. In the apparatus illustrated in the accompanying drawings there are two arms 27 for each tank 6. A chain 28 is suspended from the extremity 55 of each end of each arm 27, and these chains hang loosely within the tanks and are secured at their lower ends to the bottoms of the tanks by I-bolts 29. It will be seen that there are thus four chains 28 loosely suspended in each tank.

The shaft 26 and the arms 27 are adapted to be rocked by means of a crank arm 30 which receives its motion by means of a rod 31 eccentrically pivoted to a gear wheel 32. 60 The gear wheel 32 is driven by an electric

motor 33 mounted on a bracket 34. The rocking of the arms 27 reciprocates the upper ends of the chains 28, thus drawing the chains taut in one position and permitting them to fall slack in another position, in the 70 course of which movement the chains effect a gentle disturbance of the upper portion of the settled but unconsolidated sediment in the tank.

In Figure 3 of the drawings a modified 75 arrangement is illustrated for moving the chains 28 by reciprocating their upper ends. In the arrangement shown in this figure the chains 28 are alternately drawn taut and allowed to fall slack by the movement of a 80 rocker arm 35 which is carried by a shaft 36 and receives its motion from a cam 37 mounted on a rotatable shaft 38. The cam shaft and rocker arm shaft are supported by suitable bearings (not shown) mounted 85 on a bracket 39. The chains are guided in the proper position by grooved wheels 40, which are supported by suitable bearings and brackets. The movement of the rocker arm 35 causes the chains 28 to alternately 90 pull taut and fall slack, but as the concentrate settles and packs in the bottom of the tank, the slack portion in the chains moves upward progressively.

Where the tanks 6 are arranged in pairs, 95 as shown in Figure 2, a by-pass pipe 41 having a valve 42 is provided between the two tanks. Preferably this by-pass pipe 41 communicates with the tanks 6 at a level intermediate that of the pipes 20 and 21. The 100 by-pass pipe 41 serves to convey unsettled pulp from the top of the filled tank to the adjacent tank which is being filled.

In Figure 4 I have represented a modified form of apparatus embodying certain 105 fundamental aspects of the invention. The tank 6 of this apparatus is of the same general construction as hereinbefore described. Within the tank a stirring arm 43 rests upon a body of settled solid particles 44. The 110 stirring arm is carried by a square shaft 45 which runs through a square hole in a bevel gear 46. The upper end of the square shaft 45 is connected by means of a swivel 52 to one end of a cable 47, which passes over pulleys 48 and has attached to its other end a counter weight 49. The bevel gear 46 has an extended hub (not shown) which is supported in a bearing 53 and is driven by a bevel pinion 50 secured to the same shaft as 115 a pulley 51, the latter being adapted to be driven from any suitable power source.

In the operation of the apparatus illustrated in Figs. 1, 2 and 3 of the drawings, the pulp to be treated is fed or introduced 120 into the tank 6 with the least possible disturbance of the contents of the tank. As the pulp flows down the perforated or slotted pipe 17, it naturally emerges therefrom principally through those holes which are 125 130

immediately above the surface of the consolidated sediment. As the tank gradually fills with settled mineral the pipe 17 also fills correspondingly with settled material. The 5 solid particles emerging from the pipe 17 settle to the surface of the previously consolidated sediment, and due to the relatively great depth of the tank, the settled solid particles build up to a correspondingly great depth, 10 in the course of which building up of the settled particles their weight becomes effective in squeezing liquor out of the settled mass. The movement of the chains 28 permits a more effective and complete separation 15 of the liquor from the settling solid particles. As will be readily understood, the movement of the chains is confined to that part of their length which is above the consolidated sediment. As the sediment gradually accumulates the slack part of the chain 20 gradually moves up, its lower portion becoming progressively immobilized by the tightly packed or consolidated sediment.

Since the movement of the chains is slow, 25 say from twenty to sixty cycles per minute, and, except where the slack part comes, they move in line with themselves, it will be seen that the pulp in the portion of the tank above the mass which is in process of consolidation receives very little agitation or disturbance from them.

As is well known to those skilled in the art, a mass of mineral particles, in settling from a mineral pulp, displays several more 35 or less distinct layers or zones. In the upper zone the separation of mineral particles from relatively dilute pulp is of the nature of "free settling" as that term is generally understood in ore-dressing. Farther down 40 a zone of "hindered-settling" occurs, where the pulp has assumed greater density, and the movement of the mineral particles is restricted by the movement of neighboring particles. Below this, in turn, there is a 45 zone in which, unless interfered with in some way, the movement of the mineral particles becomes extremely slow. In this zone there is still considerable interstitial liquor, but a condition of equilibrium has almost 50 been reached. This zone I term "the zone of consolidating pulp," and the function of the chains 28 or of the stirrer 43 is to supply to this zone the interference or gentle stirring which is necessary to upset the 55 natural equilibrium and cause the mineral particles to assume their maximum possible closeness of packing, thus creating the lowest and final zone, that of complete consolidation, in which movement of individual 60 particles is finally suppressed.

The chains 28 or the stirrer 43 facilitate the transition from the state of "consolidating pulp" to that of consolidated sediment, by creating momentary "pipes" or crevices 65 within the mass, which at this point has the

consistency of "quicksand." These openings have less resistance to the upward flow of water than have the minute interstitial spaces of the mass and the water or liquor is thereby permitted to rush to these openings from the interstitial spaces of the surrounding mass and thus escape against less resistance than if it had no such assistance. The intrinsic weight of the settling material contributes to this action, and the result is that, when freed of colloids by the 70 method of the above described copending application, the final or consolidated layer of mineral particles is packed into the 75 smallest compass consistent with the density 80 and shape of the mineral particles, and the depth of the final settled mass. The movement of the chains 28, or of the stirrer 43, also contributes to the tendency of the zone 85 of hindered settling to force upward these 90 casual grains of lighter minerals, such as gangue minerals, which may occur in the pulp.

The heavy mineral particles constituting the bulk of those contained in the feed to 95 the tank are thus currently consolidated, whilst the lighter minerals tend to be carried upward and form the upper layer of the settled mass when the filling of the tank is finally completed. 100

As previously stated, the function of the stirrer 43 is the same as that of the chains 28. It consists of a hub bearing two or more blades, secured to the square shaft 45 and rotating slowly therewith, say at from five to twenty revolutions per minute. The 105 blades may be made of steel, cast iron, or wood and the lower or acting faces of the blade are sloped so as to make an angle of about thirty to forty-five degrees with the horizontal, the lower edges of the blades being the following edges as the stirrer is rotated.

In Figure 4, therefore, the right hand blade is moving toward the eye, and the effect of the inclination of the blades, combined with their rotation, is to produce a "feathering" or "smearing" action upon the surface of the sediment, facilitating the 110 packing thereof and gradually forcing the 115 stirrer upward as the resistance of the sediment gradually increases.

In the operation of the apparatus, attention being directed to Figures 1 and 2, and assuming that at the commencement of operation both tanks are empty, the door plate 8, secured water tight and the chain-moving mechanism in operation, the pulp is turned into the right hand tank by opening the valve 19 in the feed pipe 18. 120

The pulp flows down the perforated pipe 17 into the tank 6 and the solids commence to settle out on the bottom of the tank. The consolidated sediment gradually accumulates, the chains 28 and the pipe 17 125

functioning as herein previously described, and after a time the tank fills with water to the overflow pipe 20. Since, as before described, the perforated pipe 17 provides 5 for delivering substantially all of the feed to the top of the slowly rising layer of sediment, and the gentle movement of the chains is insufficient to seriously disturb the conditions of settling in the upper or free- 10 settling zone of pulp, the liquor which reaches the overflow pipe 20 during most of the period of filling the tank, is almost free of valuable mineral particles but contains the deflocculated colloidal constituents in ac- 15 cordance with the process described and claimed in my aforesaid copending applica- tion.

This colloid-bearing overflow liquor is taken to waste, or, if it contains sufficient 20 valuable mineral, to a settling tank, such as a Dorr tank, having a large settling capacity as compared with that of the tall tanks of the present invention. From the Dorr tank the overflow may be run to waste 25 or otherwise disposed of, and the settled material returned to the feed to the tall tanks or otherwise treated.

When the operation of filling the tank 6 has progressed to the point where it is nearly 30 full of consolidated sediment the feed valve 19 on the left hand tank of Figure 2 is opened and the feed pulp allowed to flow into that tank, and then the feed valve 19 on the first filled tank is closed. The valve 42 35 in pipe 41 is then opened and the material below the level of pipe 20 is drained into the left hand tank 6 until it no longer flows through pipe 41. Valve 42 is then closed and valve 22 in pipe 21 is opened and the 40 upper layer of settled material above the pipe 21 is sluiced, by the aid of wafer from a hose, through pipe 21 the launder 23 and thence to the concentrated mill for retreat- 45 ment or to other appropriate place of dis- posal. The door plate 8 is then removed from the filled tank and swung out of the way, as indicated by broken lines in Figure 1.

The car-loader 13 and car 15 are then 50 moved to their appropriate positions with respect to one another and to the doorway 7 of the tank 6 and the car loader is started. The consolidated sediment of mineral par- 55 ticles in tank 6 will ordinarily stand firmly until it is dug into with bars. It is accord- 60 ingly now barred down at a rate suitable to the capacity of car loader 13, the tapered shape of the interior of the tank facilitating the gradual downward movement of the mass. The motion of the chains may be 65 permitted to continue or, if the downward movement of the settled mass should en- danger the mechanism to which they are attached, they may be disconnected from the rocker arms 27 and secured to a beam

or bar laid across the top of tank 6, so as to securely limit their possible downward movement. If this is done the downward travel of the consolidated sediment sometimes may be facilitated by reaching in 70 through the doorway 7 with a hooked rod or other suitable tool and pulling the slack of the chains downward.

The number of chains 28 to be used in a tank of given size to be used in a 75 tank of given size to give the best results must be determined by experimentation for each set of conditions, as must also be their size, stroke, number of movements per minute and spacing. Good results under average conditions will be secured by using ordinary steel coil chain made of $\frac{1}{4}$ inch round steel, giving it a strike of 12 to 18 inches and moving it at the rate of twenty to sixty cycles per minute.

I have found that good results may be se- 85 cured by spacing the chains from eight to twelve inches from the walls of the tank and from one another. If they are too close together they may agitate the pulp too much, and if too far apart they may not sufficiently 90 facilitate the escape of liquor from the zone of consolidating pulp.

I claim:

1. An apparatus for the treatment of 95 pulps comprising a tank relatively deep as compared with its other dimensions, and adapted to contain a pulp, movable means longitudinally disposed within the tank and extending throughout substantially its entire depth for effecting a gentle disturbance 100 throughout the entire depth of pulp in the tank, and means permitting the separate removal from the tank of the settled solid particles and the supernatant liquor.

2. An apparatus for the treatment of 105 pulps comprising a tank relatively deep as compared with its other dimensions, and adapted to contain a pulp, a resilient ele- 110 ment longitudinally disposed within the tank and extending throughout substantially its entire depth, means for moving said ele- 115 ment so as to effect a gentle disturbance of the pulp in the tank, and means permitting the separate removal from the tank of settled solid particles and supernatant liquor.

3. An apparatus for the treatment of 120 pulps comprising a tank relatively deep as compared with its other dimensions and adapted to contain a pulp, a chain suspended 125 within the tank, means for moving said chain so as to effect a gentle disturbance throughout the entire depth of pulp in the tank, and means permitting the separate removal from the tank of settled solid par- 130 ticles and supernatant liquor.

4. An apparatus for the treatment of 130 pulps comprising a tank relatively deep as compared with its other dimensions, and adapted to contain a pulp, a chain loosely

hung within the tank and extending throughout substantially the entire depth of the tank, means for moving said chain so as to effect a gentle disturbance of the pulp in the tank, and means permitting the separate removal from the tank of settled solid particles and supernatant liquor.

5. An apparatus for the treatment of pulps comprising a tank relatively deep as compared with its other dimensions, and adapted to contain a pulp, a chain suspended within the tank and secured at its lower end near the bottom of the tank, a reciprocatory member near the top of the tank to 10 which the upper end of the chain is secured, and means for reciprocating said member and thereby imparting to said chain sufficient motion to effect a gentle disturbance of the pulp in the tank.

15. 6. An apparatus for the treatment of pulps comprising a tank relatively deep as compared with its other dimensions, and adapted to contain a pulp, a feed pipe arranged within said tank and provided with 20 a plurality of outlets positioned at different levels, a resilient element longitudinally disposed within the tank and extending throughout substantially its entire depth, means for moving said element so as to effect 25 a gentle disturbance of the pulp in the tank, means permitting the separate removal from the tank of settled solid particles and supernatant liquor, and means positioned intermediate the top and bottom of 30 the tank for permitting the withdrawal of material from the tank.

35. 7. An apparatus for the treatment of pulps comprising a tank relatively deep as

compared with its other dimensions, and adapted to contain a pulp, a feed pipe arranged within said tank and provided with a plurality of outlets positioned at different levels, a plurality of chains loosely suspended within the tank and having their lower ends secured near the bottom of the tank, a reciprocatory member near the top of the tank to which the upper ends of said chains are secured, means for reciprocating said member and thereby imparting to said chains sufficient motion to effect a gentle disturbance of the pulp in the tank, and means permitting the separate removal from the tank of settled solid particles and supernatant liquor.

8. An apparatus for the treatment of pulps comprising a tank relatively deep as compared with its other dimensions, and adapted to contain a pulp, a feed pipe arranged within said tank and provided with a plurality of outlets positioned at different levels, a plurality of chains suspended within the tank and having their lower ends secured near the bottom of the tank, means for reciprocating the upper ends of said chains and thereby imparting to the chains sufficient motion to effect a gentle disturbance of the pulp in the tank, a discharge opening near the bottom of the tank for removing settled solid particles therefrom, an outlet near the top of the tank for the withdrawal of liquor therefrom, and means intermediate the top and bottom of the tank for effecting the withdrawal of material from the tank.

In testimony whereof I affix my signature.
WALTER O. BORCHERDT.
